DESIGN FOR A DIE OR THE LIKE

Ramiro Moure, New York, N. Y.

Application November 10, 1938, Serial No. 81,023

Term of patent 14 years

To all whom it may concern:

Be it known that I, Ramiro Moure, a citizen of the Republic of Spain, residing at New York, in the county of New York and State of New York, have invented a new, original, and ornamental Design for a Die or the Like, of which the following is a specification, reference being had to the accompanying drawing, forming part thereof.

The shading indicates contrasting colors.

I claim:

The ornamental design for a die or the like, as shown and described.

RAMIRO MOURE.
